Inventors

UNITED STATES PATENT OFFICE.

JOHN H. STOKES AND ALBERT A. JOHNSON, OF FREEHOLD, NEW JERSEY.

DESIGN FOR A BALL-BEARING HUB.

SPECIFICATION forming part of Design No. 29,946, dated January 3, 1899.

Application filed December 10, 1898. Serial No. 698,919. Term of patent 7 years.

To all whom it may concern:

Be it known that we, JOHN H. STOKES and ALBERT A. JOHNSON, citizens of the United States, and residents of Freehold, Monmouth county, State of New Jersey, have invented and produced a new and original Design for Ball-Bearing Hubs, of which the following is a specification, reference being had to the accompanying drawings, forming part thereof.

Figure 1 is a side view of a hub, showing our new design; and Fig. 2 is an end view of the same.

As shown in the drawings, our design consists of a cylindrical body having a central portion of substantially uniform diameter, as at 1, which increases toward the opposite ends of the hub, as at 2 2, and terminates in two

raised flanges 3 3, the outer faces of which latter are flat and form the extreme end lines of the hub, this latter feature of the outer face of the raised spoke-flanges 3 3 forming the end lines of the hub being the leading or material feature of the design.

Having thus described our invention, what we claim as new, and desire to secure by Letters Patent, is—

The design for a ball-bearing hub, substantially as herein shown and described.

JOHN H. STOKES.
ALBERT A. JOHNSON.
